UNITED STATES PATENT OFFICE.

WILLIAM A. McCARTER, OF TOPEKA, KANSAS.

DENTAL EXPANSION-ARCH.

1,395,922.

Specification of Letters Patent.

Patented Nov. 1, 1921.

Application filed April 2, 1921. Serial No. 458,080.

To all whom it may concern:

Be it known that I, WILLIAM A. McCARTER, a citizen of the United States of America, residing at Topeka, in the county of Shawnee and State of Kansas, have invented certain new and useful Improvements in Dental Expansion-Arches, of which the following is a specification.

This invention relates to a dental expansion arch band and more particularly to improved means for engaging the ends thereof with fixed anchorages while permitting expansion of said arch band.

Further objects and advantages of the invention will be set forth in the detailed description which follows.

In the accompanying drawing:

Figure 1 is a diagrammatic view illustrating the application of the parts to a row of 20 teeth;

Fig. 2 is an elevation of one of the outer casings constituting the fixed anchorages of the arch band;

Fig. 3 is an elevation of one of the inner casings which are adapted to have interlocking engagement with the outer casings; and

Fig. 4 is a sectional view through the inner and outer casings showing them in interlocking engagement with each other.

Like numerals designate corresponding parts throughout the several figures of the drawing.

Expansion arch bands are in common use by orthodontists and are used for the correction of irregular teeth. Some of these arch bands are in the form of a bar and others are in the form of a wire. I may use either a bar or a wire provided its ends are adapted to enter the openings of the jack screws hereinafter described. I prefer to use a 19 gage wire indicated at 5. The ends of the wire enter bores or openings 6 formed in jack screws 7. The screws 7 are threaded into openings 8 of rectangular and preferably

45 substantially square casings 9. The casings 9 are provided with hooks 10 at their upper rear corners and are notched at their lower forward corners as indicated at 11. These inner casings are adapted to enter and be

50 engaged in outer casings 12. The casings 12 are secured to bands 13 adapted to embrace the teeth 14 in the usual and well known way and to constitute anchorages for the casings 12. The bottoms of the casings 12

55 are closed, as indicated at 14 but the tops of said casings are open and the front walls of

said casings extend upwardly for only a very short distance, the remainder of the front of said casings being open. Thus the inner casings 8 may be slipped into the 60 outer casings 12 with a lateral movement and may then be thrust downwardly therein, to cause the notched portions 11 of the inner casings to engage behind the short front wall 15 of the outer casings and to cause the 65 hooks 10 to engage over the upper edges of the rear walls of the outer casings.

It is manifest that by screwing outwardly upon the jack screws the arch band will be 70 expanded and that the inner and outer casings at this time complementally constitute a firm anchorage for the ends of the wire or bar which constitutes the arch band. By screwing inwardly upon the jack screws the pressure upon the arch band may be quickly 75 relieved and the arch band as a whole may be bodily removed, along with the inner casings, from the outer casings, by moving the inner casings forwardly and then laterally, to disengage the hooks 10 from the rear 80 walls of the outer casings and to disengage the notch portions 11 from the front walls 15 of said outer casings.

From the foregoing description it will be seen that simple and efficient means are herein provided for carrying out the objects of the invention. It is to be understood, however, that the invention is not limited to the precise construction set forth but that it includes within its purview whatever changes 90 fairly come within either the terms or the spirit of the appended claims.

Having described my invention, what I claim is:

1. A device of the character described 95 comprising a member adapted to be secured to a fixed anchorage upon a tooth, an arch band, an extensible element engageable with an end of said arch band, a casing carrying said extensible element and interengaging members upon said casing and the first named member engageable with each other, when said casing is moved laterally and then longitudinally with respect to said member.

2. A device of the character described comprising an outer casing, means for securing the same to a tooth, an inner casing, a jack screw carried by the inner casing, said jack screw being recessed for the reception of the end of a wire and means for locking the 110 inner casing to the outer casing.

3. A structure as recited in claim 2 where-

in said locking means comprises a hook upon the inner casing adapted to engage over a wall of the outer casing.

4. A device of the character described comprising an outer casing having an open top and an open front throughout the major portion of its length but closed across its front for a short distance from the bottom, in combination with an inner casing adapted 10 to fit behind the closed front portion of the outer casing, said inner casing having a hook upon its rear wall adapted to engage

over the upper edge of the rear wall of the outer casing, a jack screw threaded into the inner casing and having a bore formed longitudinally therein and an arch band having a smooth end adapted to enter the bore of the jack screw. 15

In testimony whereof I affix my signature in the presence of two witnesses.

WILLIAM A. McCARTER.
